Inventor:
Mr. Pousson.

United States Patent Office.

NIELS POULSON, OF WASHINGTON, DISTRICT OF COLUMBIA.

Letters Patent No. 82,081, dated September 8, 1868.

IMPROVED WINDOW-SHUTTER.

The Schedule referred to in these Letters Patent and making part of the same.

TO ALL WHOM IT MAY CONCERN:

Be it known that I, NIELS POULSON, of the city and county of Washington, and District of Columbia, have invented certain new and useful Improvements in Window-Shutters; and I do hereby declare the following to be a sufficiently full, clear, and exact description thereof to enable one skilled in the art to which my said invention appertains to make and carry it into effect, reference being had to the accompanying drawings, which are made a part of this specification.

My improved window-shutters are constructed of plates of corrugated metal, attached to jointed frames, which consist of bars, hinged together in pairs, in such a manner that when lowered, a continuous corrugated surface will be presented, and when drawn up, the corrugated plates will fit together within a compact space.

The invention further consists in an improved manner of attaching the plates to the folding bars.

My invention also relates to a device for masking or protecting the vertical edges of the shutters when closed.

In the drawings—

Figure 1 is an exterior view of a window, exhibiting one-half of my improved shutter in its closed position.

Figure 2 represents a vertical section thereof at X X, fig. 1.

Figure 3 represents a horizontal section of the same at Y Y, fig. 1.

Figures 4, 5, 6, and 7, are views on a larger scale.

Figure 4 represents a vertical section of a casing or receptacle in the window-cap or lintel, with the shutter drawn up and folded within it.

Figure 5 represents a vertical section of a portion of the shutter as lowered or closed.

Figure 6 is an external view of a portion of the closed shutter.

Figure 7 represents a horizontal section of a portion of the shutter and its guiding-frame, and other accessories, in the plane indicated by the line P P in fig. 5.

Similar letters of reference indicate corresponding parts in the several figures.

A A² represent metallic bars, arranged crosswise in pairs, and hinged together at the points A' A'', after the manner of the structure familiarly known as the Jacob's ladder or lazy-tongs. To the inner bar, A, of each pair is rigidly attached a corrugated metallic plate, B, the respective edges of which are reflexed in opposite directions, as represented at b, so that when the shutter is lowered, the adjacent plates will interlock, and mutually support each other, and will thus possess the strength and rigidity of a continuous plate.

The pivot-pins A¹, at the intersections of each pair of bars, are extended laterally to a sufficient length to work in vertical slots C', formed in the faces of the boxes C, in which the elevating-cords or chains, E, are enclosed. The chains E may be connected at their upper ends to a winch, of any common and suitable construction, and at their lower ends are attached to the ends of a horizontal bar or plate, D, attached to the hinged bars A A², at their lower extremity, and constituting the base of the shutter.

The bar or plate D may be made of sufficient width to close, when elevated, the box or chamber F, which receives the folded shutter, or a separate plate, D', may be attached to the plate D for this purpose, as represented in fig. 4. In the upper portion of this fig. 4, the plates B are omitted, exposing the mortises B', in the bars A, to receive tenons on the ends of the plates B.

The shutter may be held down by a pin or bolt, K, operated from the inside of the window, and engaging in the base-bar D.

G G represent parts of the stationary window-frame.

To cover and protect the vertical edges of the shutter, I employ movable plates M, of segmental form, with scalloped edges, fitting the corrugations of the plates B. The movable plates M work in vertical slots M', in stationary plates, attached to the window-frame, so that they may be slipped within the frame, as represented by dotted lines in fig. 7, when the shutter is to be raised. In their outer position they are locked by any suitable device which may be accessible only from within the building.

In some cases it will be found preferable to make the shutters in two parts, sliding horizontally, instead of vertically, and meeting in the centre. Under this arrangement they will be very useful as doors.

From an inspection of figs. 4 and 5, of the drawings, the bars A will be seen to have, near each end, a curvature, A'''', in opposite directions. This arrangement enables me to form the mortises or recesses, B', which receive the tenons b', of the plates B, alternately in opposite edges of the bars, excepting in case of the end mortises, which are formed in the transverse centre of the bars. This disposition of the tenons on opposite edges of the supporting-bars, causes the plates to be held with great security, so that they cannot possibly be displaced when the shutters are closed.

Having thus described my invention, the following is what I claim as new therein, and desire to secure by Letters Patent:

1. I claim the combination of the folding bars A A², and corrugated plates B, when said plates are attached rigidly to the inner bars A, as herein described for the purposes specified.
2. I also claim the sliding plates M, in the described combination, with the folding shutter A A² B, to mask or protect the vertical edges of the said shutter, substantially as explained.
3. I claim the arrangement of the tenons b' b', of the plates B, alternately on opposite edges of the bars A, substantially as and for the purposes set forth.
